UNITED STATES PATENT OFFICE.

CHARLES L. SERVICE, OF ALBANY, NEW YORK.

MUSIC-LEAF TURNER.

SPECIFICATION forming part of Letters Patent No. 426,146, dated April 22, 1890.

Application filed April 12, 1889. Serial No. 307,007. (No model.)

To all whom it may concern:

Be it known that I, CHARLES LAVONIA SERVICE, a citizen of the United States, residing at Albany, in the county of Albany and State 5 of New York, have invented a new and useful Music-Leaf Turner, of which the following is a specification.

My invention relates to improvements in music-leaf turners; and the object of my invention is to provide a music-leaf turner that may be readily attached to a piano or other similar musical instrument, or to an orchestra music-stand, and be operated by the performer quickly easily with a single movement of the hand. I attain this object by the mechanism illustrated in the accompanying drawings, in which—

Figure 1 shows the mechanism for operating my leaf-turner. Fig. 2 shows the arm A and manner of attaching it to a leaf of music. Fig. 3 is a section along line xz of Fig. 1, and Fig. 4 shows the flange M.

Similar letters refer to similar parts throughout the several views.

To the under side of the ledge r of the music-rack R, I attach two or more screws or bolts a (see Fig. 2) and secure to them the flange M of the bracket P. The lower edge of the bracket P is in contact with the rack R. The flange M is provided with openings n , Fig. 4, sufficiently large to allow the head of the bolt a to pass through it, and a slot communicating with said opening not large enough to allow the head of the bolt to pass through. By this arrangement the heads of the bolts a are placed through the openings n , and a lateral movement is given the flange, and the bolts enter the slots and hold the flange securely in place.

It is very easy to attach my invention to a piano or music-rack and to remove it therefrom without injuring the finish of the piano-forte.

To the bracket P are attached the parallel 45 projecting plates E E, one above the other. Between the plates E E are placed the ends of the fingers A A A, one above the other, movable in a horizontal plane about the bolt g , passing through the plates E E and the ends 50 of the said fingers. To the bracket P, beneath the plates E E, is a projecting guide-

plate s , to which is secured the arm B by means of a bolt, allowing the arm B to be moved freely in a horizontal plane about the said bolt. On the upper surface of the arm 55 B is a stud b , which moves with the arm in contact with the guide-plate s , and the guide-plate being provided with a stop s' the arm B is limited in its movement. The arm B, which is right-angular in form, has one end 60 attached to the pivot or bolt passing through the guide-plate s and its other end projecting backward through an opening in the bracket P and provided with a spring-bar C, said spring-bar having on its upper surface the 65 catch or projection c. The spring-bar C as thus arranged passes under the fingers A A A, and the catch c engages with and passes against the rear side of the lowest finger, coming in contact with each finger in turn as they 70 are moved from one side to the other. The spring-bar C being semicircular in form, bowing upwardly, as one finger is moved from the right to the left the spring is relaxed and the catch comes into contact with the next finger 75 until they are all turned over. The arm B is attached to the bell-crank lever D by the slightly-curved link e. The bell-crank lever D is pivoted to the plate H, attached to the horizontal part of the bracket P, and has attached to it the coiled spring S at the end of the arm d, beneath which the lever L presses. The spring S is secured to the bracket P and tends to hold depressed the arm of the lever D, to which it is attached, which in turn causes 80 the spring C to be in position under the fingers A A A, ready to turn them. The lever L is fulcrumed to a projection K on the bracket P and presses against the under side of the arm d of the lever D. When the lever L is 85 pressed downward, the bell-crank lever D forces the arm B, carrying the spring-bar C, forward, which, being in contact with the finger A, causes that finger to revolve about the pin g and occupy the position denoted by dotted lines, Fig. 1. Letting go of the lever L, the spring S acts upon the bell-crank lever D, forces it back, and causes the spring-bar C to again come into contact with the next finger A on the right of the plates E E. 90

The fingers A A are usually constructed of two pieces—the one long, the other a short

piece—near the end attached to the music. (See Fig. 2.) The two pieces are secured together by the pin *o*, about which the small piece can move slightly, being limited by the 5 stud *p* in an elongated slot. This arrangement is found advisable, because the sheet of music when turned by a rigid finger becomes bent and does not work easily.

For fastening the sheet of music to the finger, I usually use the clasp *N*, which consists of two pieces of metal secured to a pivot-pin and held together by a spring and separated by pressing together the projecting ends *v v* below the pivot-pin, Fig. 2. I do not confine myself to the use of this particular clasp.

To operate my device, place a piece of music against the rack, resting on the ledge *r*, the center of the sheet, where the leaves are joined together, being on a line with the bolt 20 *g*. Attach the fingers to the lower edge of each leaf. Then when it is desired to turn the leaf press down on the lever *L*, which will cause the finger to move the leaf from the right to the left, and letting go of the lever 25 *L* the mechanism will place itself in position to turn the next leaf. When desired, the leaves may be turned back from left to right with the hand and the piece or parts of them repeated, and the mechanism will turn them 30 again when required.

This machine is extremely simple in its construction and operation, it is readily attached to an organ, piano, or music-stand, and per-

forms its functions quickly, satisfactorily, and in a positive manner.

What I claim as my invention, and desire to secure by Letters Patent, is—

1. In a music-leaf turner, the combination of a series of fingers *A*, each provided at one end with a clasp, at the other end with a pivot, 40 with the pivoted arm *B*, provided with a curved upwardly-projecting spring-bar *C*, having on the upper convex surface thereof a catch *c*, said catch coming into contact with each of the fingers *A* alternately, substantially as described. 45

2. In a music-leaf turner, a pivoted arm provided with a spring-bar having a catch thereon connected by a link to a bell-crank lever, said lever having an arm attached to a spring, said 50 arm in contact with a moving lever, substantially as described.

3. In a music-leaf turner, the combination of fingers provided at one end with a clasp, at the other end with a pivot, with a pivoted 55 arm provided with a spring-bar having a catch thereon, said catch coming into contact with each finger in turn, said pivoted arm connected by a link to a bell-crank lever, said lever having an arm attached to a spring, said 60 arm in contact with a moving lever, all substantially as described.
